(57) **CLAIM**

The ornamental design for a footwear sole, as shown and described.

DESCRIPTION

FIG. 1 is a bottom, right perspective view of a footwear sole according to my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view of a mirror image embodiment of the design of FIG. 1, this embodiment of the design also having views that are mirror images of the views shown in FIGS. 1 and 3–7; and,

(Continued)

FIG. 9 is a bottom view of the design of FIG. 1 shown alongside mirror image environment.

The broken line representations in the figures show unclaimed environment or boundaries, and thus form no part of the claimed design.

1 Claim, 7 Drawing Sheets
